UNITED STATES PATENT OFFICE.

JONATHAN A. HUNT, OF WESTBOROUGH, MASSACHUSETTS.

DESIGN FOR A BICYCLE-SADDLE.

SPECIFICATION forming part of Design No. 28,460, dated April 5, 1898.

Application filed December 6, 1897. Serial No. 660,978. Term of patent 14 years.

To all whom it may concern:

Be it known that I, JONATHAN A. HUNT, a citizen of the United States, residing at Westborough, in the county of Worcester and State of Massachusetts, have invented and produced a new and original Design for Bicycle-Saddles, of which the following is a specification, reference being had to the accompanying drawings, forming a part thereof.

My invention relates to a bicycle-saddle; and it consists in a new and original design for a bicycle-saddle, as will be hereinafter fully described.

Referring to the drawings, Figure 1 is a plan view of a bicycle-saddle, showing my design; and Fig. 2 is a rear edge view of the same.

The leading feature of my design for a bicycle-saddle consists of a rounded or curved depression in the top of the saddle at the central rear portion or edge thereof, which extends from the rear edge of the saddle to and through the rear edge of the central opening through the saddle.

In the accompanying drawings, 1 is a bicycle-

saddle showing my design of the rounded or curved depression in the top of the saddle-seat at the central rear portion thereof directly back of the central opening 3 in the saddle. The depression 2 extends from the rear edge of the saddle to and through the rear edge of the opening 3, as shown in Fig. 1, and the form of said depression is rounded or concaved in transverse section, as clearly shown in Fig. 2.

The essential feature of my design is a rounded or concaved depression in the saddle seat or cover at the central rear part thereof, which extends from the rear edge of the saddle to and through the rear edge of the central opening through the saddle.

What I claim is—

A design for a bicycle-saddle, substantially as shown and described.

J. A. HUNT.
